UNITED STATES PATENT OFFICE.

FRED D. SMITH, OF NEW CARLISLE, INDIANA, ASSIGNOR OF ONE-HALF TO
WILLIAM H. HAY, OF WATERLOO, IOWA.

ROWING-GEAR.

SPECIFICATION forming part of Letters Patent No. 240,194, dated April 12, 1881.
Application filed September 3, 1880. (No model.)

To all whom it may concern:

Be it known that I, FRED D. SMITH, of New Carlisle, in the county of St. Joseph and State of Indiana, have invented a new and Improved 5 Rowing-Gear, of which the following is a specification.

The object of this invention is to provide a device by means of which a boatman may pull a boat in the direction in which he is facing.

10 Figure 1 is a plan view showing the gear in position on a boat. Fig. 2 is a front view of the same on line α α , Fig. 1.

Similar letters of reference indicate corresponding parts.

15 In the drawings, A represents a boat, and a b c a side, gunwale, and thwart thereof.

B is an oar-lock block journaled in the standards d d —that are fastened on the gunwale b —parallel with said gunwale b , and sufficiently 20 above it for a free rocking movement inward and outward.

C is an oar constructed in two parts, the blade part f of which is pivoted or jointed to the handle g , so that said blade part f can 25 swing flatwise. In this instance the inner end of the part f has securely fastened on its upper and lower sides cleats or lugs h h , that extend, parallel with each other, beyond the end of the part f , and between these cleats or lugs h h 30 the handle g is pivoted on a pin, l . Said handle g is provided on its pivoted end with a strengthening band of metal, i , and on its under side has a perforated laterally-extending plate, k , attached for the engagement of an

35 end of the horizontal adjustable pivoting rod or brace D, said plate k being provided with several holes for the purpose of changing the fulcrum of the oar C when desired. The opposite end of this rod or brace D is hooked 40 into the inward-projecting end of a metal strap, m , that is fastened about the rear end of the oar-lock block B. On the opposite end of the block B a metal strap, n , is fastened, provided with

a hole, o , for the reception of the pin p , that projects downward from near the inner end of the part f of the oar, and serves as the pivot on which said blade part f works.

The pin p being entered in the hole o of the block B, and the free end of the brace D being engaged in one of the perforations of the plate k of the oar-handle, as shown in the drawings, the operator, sitting on the thwart c and facing in the direction of the arrow, Fig. 1, pulls on the handle g with the effect of forcing the blade f of the oar rearward, in the direction indicated by dotted lines, Fig. 1, thus forcing the boat forward in the direction in which he (the operator) is facing.

The oar-lock block B rocks easily to accommodate itself to the dip of the oar and motion of the boat, and the oar C can be readily folded out of the way against the side of the boat, and as readily be unshipped and taken in board as can an oar of ordinary construction.

To sportsmen seeking water-fowl this device is of great advantage, permitting the sportsman to keep the game in view while pulling toward it.

I do not confine myself to an oar-lock block 70 constructed precisely as herein shown and described, as said block may be made entirely of metal or of wood, and may be varied in shape.

Having thus described my invention, what I claim as new, and desire to secure by Letters 75 Patent, is—

In rowing-gear, the pivoted handle g , provided on its under side with a perforated laterally-extending plate, K , and an oar, f , pivoted thereto, in combination with the oar-lock 80 block B and the pivoted rod D, as and for the purpose specified.

FRED D. SMITH.
